CLAIM

The ornamental design for a building, as shown and described.

DESCRIPTION

FIG. 1 is a top front perspective view of a building showing the claimed design;

FIG. 2 is a front view thereof;

FIG. 3 is a left side view thereof; and,

FIG. 4 is a right side view thereof.

The dashed broken lines in the figures show portions of the building that form no part of the claimed design.

The oblique shade lines in the figures show transparency or translucency.

1 Claim, 4 Drawing Sheets(56)
